US00D679023S

(12) **United States Design Patent**
Quisenberry

(10) **Patent No.:** US D679,023 S
(45) **Date of Patent:** ** Mar. 26, 2013

(54) **FOOT WRAP**(75) Inventor: **Tony Quisenberry**, Highland Village, TX (US)(73) Assignee: **ThermoTek, Inc.**, Flower Mound, TX (US)(**) Term: **14 Years**(21) Appl. No.: **29/397,856**(22) Filed: **Jul. 21, 2011**

FIG. 1 is an unfolded perspective view of a foot wrap in accordance with the design;

FIG. 2 is a perspective view of the foot wrap of FIG. 1 in use; FIG. 3 is a perspective view of the foot wrap of FIG. 1 in use; FIG. 4 is a perspective view of the foot wrap of FIG. 1 in use; FIG. 5 is a top plan view of the foot wrap in accordance with the design; and,

FIG. 6 is a bottom plan view of the foot wrap in accordance with the design.

The features shown in broken lines in the drawings depict environmental subject matter only and form no part of the claimed design.
